(57) **ABSTRACT**

A new garden rose plant of the Compact Floribunda class
which has abundant, deep pink flowers and attractive foliage.
This new and distinct variety has shown to be uniform
and stable in the resulting generations from asexual propagation.

2 Drawing Sheets

1

Botanical designation: *Rosa hybrid*.

Variety denomination: 'Poulpal081'.

SUMMARY OF THE INVENTION

The present invention constitutes a new and distinct variety of rose plant which originated from a controlled crossing between the female seed parent, an unnamed seedling, and the male pollen parent, also an unnamed seedling. Both of the parent varieties are non-patented.

The two parents were crossed during the summer of 2011 and the resulting seeds were planted in a controlled environment in Fredensborg, Denmark. The new variety, named 'Poulpal081', originated as a single seedling from the stated cross.

The new variety may be distinguished from its male pollen parent and female seed parent primarily by the following characteristics. The male pollen parent plant has orange blend flowers while the new variety has deep pink flowers. The female seed parent plant has red flowers while the new variety has deep pink flowers.

The objective of the hybridization of this rose variety was to create a new and distinct variety with unique qualities, such as:

1. Uniform and abundant deep pink flowers;
2. Vigorous, but compact growth when propagated on its own roots;
3. Exceptional disease resistance.

This combination of qualities is not present in previously available commercial cultivars of this type, known to the inventor, and distinguish 'Poulpal081' from all other varieties of which we are aware.

2

As part of the rose development program, Mogens N. Olesen germinated the seeds from the aforementioned hybridization during winter of 2011 and conducted evaluations on the resulting seedlings in a controlled environment in Fredensborg, Denmark. 'Poulpal081' was selected in the spring of 2012 by the inventor as a single plant from the progeny of the aforementioned hybridization.

Asexual reproduction of 'Poulpal081' by rooted cuttings was first done by Mogens N. Olesen in the nursery in Fredensborg, Denmark in July, 2012. This initial and other subsequent asexual propagations conducted in controlled environments have demonstrated that the characteristics of 'Poulpal081' are true to type and are transmitted from one generation to the next.

DESCRIPTION OF THE DRAWING

The accompanying color illustrations show as true as is reasonably possible to obtain in color photographs of this type, the typical characteristics of the buds, flowers, leaves, and stems, of 'Poulpal081'.

Specifically illustrated in FIG. 1 of the drawings are open flowers, sepals detached showing reproductive flower parts.

Specifically illustrated in FIG. 2 of the drawings are stems and leaves. Plants shown are 2 years of age.

DETAILED DESCRIPTION OF THE VARIETY

The following is a description of 'Poulpal081', as observed in its growth in a field nursery in Linn County, Oreg. Observed plants are 2 years of age, and were grown on their own roots. Color references are made using The Royal Horticultural Society (London, England) Colour Chart, 2001, except where common terms of color are used.

For a comparison, several physical characteristics of the rose variety 'Poulcas031', U.S. Plant Pat. No. 22,502 are compared to 'Poulpal081' in Chart 1.

CHART 1

	'Poulpal081'	'Poulcas031'
Petal Count	65 petals	40 to 50 petals
Flower Diameter	70 mm	70 to 80 mm
General Tonality of Flower Color	Red-Purple Group N57A	Purple Group N57A

FLOWER AND FLOWER BUD

Blooming habit: Continuous.
Flower bud:

Size.—Upon opening, 20 mm in length from base of receptacle to end of bud. Bud diameter is 14 mm.

Bud form.—Globose.

Bud color.—As sepals divide petals are Red Group 46C and 46A.

Sepal inner surface.—Color: Yellow-Green Group 146D. Surface: Lightly pubescent.

Sepal outer surface.—Color: Yellow-Green Group 144A with intonations of Greyed-Red Group 179A. Texture: Smooth.

Sepal shape.—Apex: Cirrhose. Base: Flat at union with receptacle.

Sepal margin.—Margins have moderate foliaceous appendages on three of the five sepals.

Sepal size.—24 mm long, 9 mm wide.

Receptacle.—Texture: Smooth. Size: 6 mm in height, 6 mm wide. Color: Yellow-Green Group 144A with intonations of Greyed-Purple Group 183B. Shape: Campanulate.

Pedicel.—Surface: Smooth. Length: 20 mm. Diameter: 2 mm on average. Color: Yellow-Green Group 144A.

Strength: Strong.

Peduncle.—Length: 3 to 10 cm. Diameter: About 3 mm. Color: Yellow-Green Group 147B. Texture: Small prickles.

Flower bud development: Flower buds are borne in clusters of about 3 flower buds per stem.

Flower bloom:

Fragrance.—Moderate, clove like fragrance.

Duration.—The blooms have a duration on the plant of approximately 14 days. Petals fall cleanly away from plant after flowers have fully matured.

Size.—Flower diameter is 70 mm when open. Flower depth is 33 mm.

Flower shape.—Rosette, very double.

Shape of flower, side view.—The upper portion is flat. The lower portion is flat convex.

Petalage: Under normal conditions, flowers have about 65 petals.

General tonality of flower: Open flowers are Red-Purple Group N57A.

Petal color:

Upon opening, outer and inner petals.—Upper surface: Red Group 61B. Lower surface: Red-Purple Group 63B with other intonations of Red-Purple Group 70A.

Basal petal spots, upon opening.—Upper surface: Yellow Group 2B. Lower surface: Yellow Group 2B.

After opening, outer and inner petals.—Upper surface: Red Group 61B. Lower surface: Red-Purple Group 63B with other intonations of Red-Purple Group 70A.

Basal petal spots, after opening.—Upper surface: Yellow Group 2B. Lower surface: Yellow Group 2B.

Petals:

Petal reflex.—Somewhat reflexed.

Margin.—Entire and uniform. Moderate to strong undulations.

Shape.—Broad and elliptic. Apex shape: Rounded. Base shape: Acute.

Size.—30 mm (l)×35 mm (w).

Texture.—Smooth.

Thickness.—Average.

Petaloids:

Size.—23 mm (l) by 20 mm (w).

Quantity.—10 to 15.

Shape.—Elliptical with an acute base and rounded apices.

Color.—Upper surface is Red Group 61B. Lower surface Red-Purple Group 63B. Petaloid sport is Yellow Group 2B.

25 Reproductive flower parts:

Pollen.—None observed.

Anthers.—Size: 2 mm in length. Color: Yellow Group 13B. Quantity: 50 on average.

Filaments.—Color: Yellow Group 9B. Length: 6 mm.

Pistils.—Length: 5 mm. Quantity: 15 on average.

Stigmas.—Color: Yellow-White Group 158A.

Styles.—Color: Yellow-White Group 158A.

Location of stigmas.—Inferior in location relative to the length of the filaments and the height of the anthers.

Hips.—None Observed.

PLANT

40 Plant growth: Upright, bushy. Plants are 32 cm in height, and 30 cm wide.

Stems:

Color of juvenile growth.—Yellow-Green Group 146C.

Color of mature growth.—Yellow-Green Group 146C.

Length.—Canes are about 10 cm from the base of the plant to the flowering portion.

Diameter.—About 5 mm.

Internodes.—On mature canes about 30 mm between nodes.

Surface texture.—Young wood: Smooth. Older wood: Smooth.

Long prickles:

Incidence.—2 prickles per 10 cm of stem.

Size.—Average length of prickles on mature stems is 5 mm.

Shape.—Upper portion is linear. Lower portion is concave.

Color.—Juvenile prickles: Greyed-Orange Group 174B. Mature prickles: Greyed-Orange Group 174B.

60 Plant foliage:

Compound leaf.—125 mm (l)×90 (w).

Quantity.—3 leaves per 10 cm of stem on average.

Leaf bearing angle to the stem.—45 degrees.

Color of juvenile foliage.—Upper side: Yellow-Green Group 144A. Lower side: Yellow-Green Group 144B.

Color of mature foliage.—Upper side: Yellow-Green Group 147A with a marginal intonation of Greyed-Purple Group N186C. Lower side: Yellow-Green Group 146B.

Plant leaves and leaflets:

Stipules.—Size: 10 mm long, mm wide. Quantity: 2 per compound leaf. Shape: Linear, slightly broad based with outward extending apices. Margins: Finely serrated. Color: Yellow-Green Group 144A.

Petiole.—Length: 15 mm. Diameter: 2 mm. Upper surface color: Yellow-Green Group 144A and Greyed-Purple Group 183A. Lower surface color: Yellow-Green Group 144A.

Rachis.—Length: 6 mm. Upper surface color: Yellow-Green Group 144A and Greyed-Purple Group 183A. Lower surface color: Yellow-Green Group 144A.

Leaflet.—Quantity: Normally 5 to 7 leaflets. Margins: Serrated. Size: Terminal leaflets are about 50 mm long, 35 mm wide. Shape: Generally elliptical. Base: Rounded. Apex: Acute. Texture: Smooth. Thickness:

Average. Arrangement: Odd pinnate. Venation: Reticulate. Glossiness: Moderately glossy.

Disease resistance: Above average resistance to powdery mildew *Sphaerotheca pannosa*, downy mildew *Peronospora sparsa*, rust *Phragmidium* sps., black spot *Diplocarpon rosae*, and *Botrytis cinerea* under normal growing conditions.

Cold hardiness: The variety is tolerant to USDA Cold Hardiness Zone 6.

Heat tolerance: The variety has been found to be suitable for climate conditions found in the American Horticulture Society heat zone 7.

We claim:

1. A new and distinct variety of rose plant of the Compact Floribunda rose class named 'Poulpal081', substantially as illustrated and described herein, due to its abundant deep pink flowers, disease resistance, and extended period of bloom.
